DOOR AND LATCH COMBINATION

Kent W. Benham, Gates Mills, Ohio, assignor to The Sanymetal Products Co., Inc., Cleveland, Ohio, a corporation of Ohio

Filed Nov. 13, 1958, Ser. No. 53,366

Term of patent 14 years

(Cl. D50—5)

Fig. 1 is a side elevational view of a door and latch combination showing my new design;

Fig. 2 is a fragmentary enlarged perspective view of portions shown in full lines in Fig. 1; and

Fig. 3 is a front view of said portions.

The other side not shown is substantially the same as the side shown except that it does not have a handle.

The essential features of my design reside in the portions shown in full lines.

I claim:

The ornamental design for a door and latch combination, substantially as shown and described.
